UNITED STATES PATENT OFFICE.

WALTER E. LOMBARD, OF ARLINGTON, MASSACHUSETTS.

SPREADING DEVICE.

Application filed November 10, 1922. Serial No. 600,061.

To all whom it may concern:

Be it known that I, WALTER E. LOMBARD, a citizen of the United States of America, and a resident of Arlington, in the county 5 of Middlesex and State of Massachusetts, have invented certain new and useful Improvements in Spreading Devices, of which the following is a specification.

This invention relates to devices for 10 spreading members apart, being particularly adapted for use in the construction of steel buildings to separate the steel plates on one member sufficiently to admit the end of another member to be riveted thereto.

Ordinarily these plates are parallel and separated the required distance but in transportation, the plates are sometimes bent inwardly so that the member to be connected thereto cannot be inserted between the 20 plates.

The present practice is to force the plates into required separated position by means of sledge hammers and the like.

This entails considerable labor and consumes a great amount of time which could be utilized to better advantage by the workmen.

To overcome this difficulty and provide a simple device for quickly separating the 25 plates when out of parallelism is the object of the present invention.

While it is evident that the device is adapted to be used for the purpose described, it is adapted to be used also for many other 30 similar purposes, as must be perfectly obvious.

The invention consists primarily of a casing adapted to be positioned upon the tops of the plates and provided with reciprocating 40 means to be interposed between the plates and operated by crank mechanism through a plurality of gears confined within the casing.

The invention further consists in certain 45 novel features of construction and arrangement of parts which will be understood readily by reference to the description of the drawings and to the claims to be herein-after given.

For the purpose of illustrating the invention, one preferred form thereof is shown 50 in the drawings, this form having been found to give satisfactory and reliable results, although it is to be understood that 55 the various instrumentalities of which the invention consists can be variously arranged

and organized, and that the invention is not limited to the precise arrangement and organization of the instrumentalities as herein shown and described, except as required by 60 the scope of the appended claims.

Of the drawings:

Figure 1 represents a plan of a device embodying the principles of the present invention. 65

Figure 2 represents a vertical section on line 2, 2 on Fig. 1.

Figure 3 represents a vertical section on line 3, 3 on Fig. 1.

Figure 4 represents an inverted plan of 70 the cover and members carried thereby, and

Figure 5 represents a plan of the device with the cover removed.

Similar characters indicate like parts throughout the several figures of the drawings. 75

In the drawings, 10 is a frame or casing provided with a handle 11 by which the device may be carried from point to point. The frame or casing 10 is provided with a 80 cover 12 secured thereto by means of screws 13. The frame 10 is provided with alined bearings 14, 15, one of which, 14, is larger than the other.

In the bearing 14 is disposed a cylindrical 85 ram 16 having a head 17 on the outer end thereof. This ram 16 is provided with a cylindrical axial recess 18 in which is disposed the threaded shank 19 of a ram 20 positioned in the bearing 15 and having a head 21 on 90 the outer end thereof.

The frame 10 has fixedly secured thereto a key 22 extending into a slot 23 formed in the periphery of the ram 16, and lengthwise thereof, thereby preventing said ram 95 from rotating about its axis in the bearing 14. A key 24 is similarly fixedly secured in the frame 10 with a portion thereof extending into a slot 25 in the periphery of the ram 20, thereby preventing the rotation of 100 said ram about its axis within the bearing 15.

The frame 10 is also provided with a barrel 26 midway between the opposite ends of the frame 10 and in axial alinement with the bearings 14 and 15. The bore 27 of this 105 barrel 26 forms a guide for the ram 16, and the threaded shank 19 of the ram 20 fits the bore 18 of the ram 16, the wall of said bore forming a guide for said threaded shank. Between the ends of the barrel 26 and the 110 inner end walls of the casing or frame 10 are disposed the nuts 28 and 29, which are

prevented from end movement by the hubs thereof contacting with the ends of the barrel 26 and the inner walls of the casing or frame 10.

5 The nut 28 is mounted upon the threaded portion 30 of the ram 16, and the nut 29 is mounted upon the threaded shank of the ram 20. It is obvious, therefore, that when the nuts 28 and 29 are rotated about their axes, the rams 16 and 20 will be reciprocated simultaneously. The nut 28 has formed thereon or secured thereto a beveled gear 31, and the nut 29 has similarly mounted thereon a beveled gear 32. The teeth of these beveled 10 gears 31 and 32 mesh with a driving gear 33, having a pinion 34 formed upon or secured to the hub thereof.

15 The pinion 34 meshes with the teeth of a gear 35 rotatable about a stud 36 secured to the cover 12, said gear 35 having formed thereon a pinion 37 which meshes with the gear 38 revoluble about the axis of the shank 39 of the driving gear 33.

20 This gear 38 has a tubular hub 40 extending through the cover 12 and to the outer end of the tubular hub 40 is secured an actuating crank 41. Secured to the outer end of the shank 39 by means of a pin 42 is a collar 43 to retain the various elements in 25 position when the cover 12 is removed from the casing or frame 10.

25 By turning the actuating crank 41, the gear 38 will be rotated about its axis, driving the pinion 37 and gear 35, said gear 35 in turn rotating the pinion 34 and gear 33. This latter gear meshing with the gears 32 and 31 will rotate the nuts 28 and 29 about their axes and cause the rams 16 and 20 to be moved endwise relatively to each other 30 in either direction as desired.

35 The inner end of the ram 16 will remain within the bore 27 of the barrel 26, and the inner end of the threaded shank 19 of the ram 20 will remain within the bore 18 of the ram 16 when the heads 17 and 21 are moved outwardly to the full limit of their 40 movement.

45 While only two gears 38, 35 and pinions 37, 34 are shown in the drawings, it is obvious that a greater number of gears may be used in the train of gearing if it is desired to attain a greater degree of leverage.

50 The cover 12 is provided with oppositely disposed wings 44, 45, which wings are adapted to rest upon the tops of the steel plates which it is desired to spread apart. These wings 44, 45 are provided with grooves 55 46 extending laterally thereof, in which are disposed the slideable bars 47, 48, having downwardly extending flanges 49 at the opposite ends thereof.

55 These bars 47, 48 are provided with slots 50 through which extend the non-revoluble threaded shank 51 having a clamping nut 52 mounted on the upper end thereof.

When it is desired to use the device in connection with the erection of a steel construction building, to separate the plates of a steel column sufficiently to permit the admission of the lower end of another column 70 to be riveted thereto, the operator, by means of the handle 11, carries the device to the place where it is needed. He then places the wings 44, 45 upon the upper ends of the plates of the column and adjusts the bars 47, 75 48 so that the flanges 49 will bear against the opposite edges of the plates. The device will then be positioned in such a manner that it cannot be accidentally displaced.

80 The operator then grasps the actuating handle 41 and rotates the driving gear 33 in the manner described, thus causing the nuts 28 and 29 in their rotation to move the rams 16 and 20 in opposite directions, the heads 17 and 21 bearing against the inner faces of the plates and forcing them apart, the operator continuing the rotation of the actuating member until the plates are separated a sufficient amount.

85 This makes a very convenient and simple 90 device for accomplishing this purpose.

It is believed that the operation and many advantages of the invention will be understood readily without further description.

Having thus described my invention, I 95 claim:

1. The combination of a frame having oppositely disposed outwardly extending wings; gearing supported by said frames; means for actuating said gearing; and a 100 non-revoluble member reciprocable in bearings in said casing and provided with a head on the outer end thereof.

2. The combination of a frame having oppositely disposed outwardly extending wings; 105 positioning members on said wings; gearing supported by said frame; means for actuating said gearing; and a non-revoluble member reciprocable in bearings in said casing and provided with a head on the outer 110 end thereof.

3. The combination of a frame having oppositely disposed outwardly extending wings; members adjustable laterally of said wings and having down-turned flanges; gearing 115 supported by said frame; means for actuating said gearing; and a non-revoluble member reciprocable in bearings in said casing and provided with a head on the outer end thereof.

120 4. The combination of a frame having oppositely disposed outwardly extending wings; members slidably mounted on said wings and movable laterally thereof; means for retaining said slideable members in adjusted 125 position; gearing supported by said frame; means for actuating said gearing; and a non-revoluble member reciprocable in bearings in said casing and provided with a head on the outer end thereof.

5. The combination of a frame having alined bearings; a reciprocating non-revoluble member in each bearing; gearing for simultaneously reciprocating said members; and a rotatable crank for actuating said gearing.

6. The combination of a frame having alined bearings; a reciprocating member in one bearing having an axial recess; a reciprocating member within and fitting said recess; and manually actuated gearing for reciprocating said members.

7. The combination of a frame having alined bearings; reciprocating members in said bearings, one telescoping into and fitting the cylindrical bore of the other, and each member being provided with a screw thread; means preventing the rotation of said members; a revoluble nut on each member; means preventing end movement thereof; and manually actuated gearing for rotating said nuts.

8. The combination of a frame having alined bearings; reciprocating members in said bearings, one telescoping into the other, and each member being provided with a screw thread; means preventing the rotation of said members; a revoluble nut on each member; means preventing end movement thereof; a bevel gear on each nut; an intermediate bevel gear meshing with and driving both nut gears; and manually actu-

ated gearing for rotating said driving gear.

9. The combination of a frame having alined bearings; reciprocating threaded members in said bearings, one telescoping into the other; means preventing the rotation of said threaded members; a revoluble nut on each member restrained from end movement; a single driving gear meshing with and rotating both nuts simultaneously; an actuating member; and a train of gears for transmitting motion from said actuating member to said driving gear.

10. The combination of a frame having alined bearings; reciprocating threaded members in said bearings, one telescoping into the other; means preventing the rotation of said threaded members; a revoluble nut on each member restrained from end movement; a bevel gear on each nut; a driving gear meshing with both bevel gears and rotating both nuts simultaneously; an actuating member; and a train of gears for transmitting motion from said actuating member to said driving gear.

Signed by me at 746 Old South Building, Boston, Mass., this 9th day of November, 1922.

WALTER E. LOMBARD.

In presence of—

NATHAN C. LOMBARD,
H. V. PINKERTON.
